UNITED STATES PATENT OFFICE.

WILLIAM S. BURNETT AND WILLIAM HERBERT GOODALL, OF MILWAUKEE,
WISCONSIN.

MULTIPLEX TELESIG.

SPECIFICATION forming part of Letters Patent No. 705,511, dated July 22, 1902.

Application filed April 6, 1900. Serial No. 11,791. (No model.)

To all whom it may concern:

Be it known that we, WILLIAM S. BURNETT and WILLIAM HERBERT GOODALL, citizens of the United States, and residents of Milwaukee, county of Milwaukee, and State of Wisconsin, have invented new and useful Improvements in Multiplex Telesigs, of which the following is a specification.

Our invention relates to improvements in electrical station-individualizing devices, and pertains especially to a device for individualizing the various stations on an electric signaling-circuit, which for the sake of brevity we have termed a "multiplex telesig."

The object of our invention is to provide means whereby an operator at one station, usually (but not necessarily) a central station, may individualize any one of the other stations on a single or double electrical circuit and signal or transmit messages to that station independently of the other.

In the following description, reference is had to the accompanying drawings, in which—

Figure 1 is a side view of the apparatus used at the local stations (hereinafter termed the "key mechanism") with a diagrammatic illustration of a light and signal bell used in connection therewith and also of the central-office batteries and switch-lever. Fig. 2 is a top view of the key mechanism. Fig. 3 is a view of the same from the opposite side from that shown in Fig. 1. Fig. 4 is an enlarged vertical sectional view of the carrier. Fig. 5 is a detail showing mechanical means for driving the carrier in which the key-actuating pins are mounted. Fig. 6 is a top view, partly in horizontal section, of the key-guide. Figs. 7 and 8 are details illustrating modified forms of the switch-key. Fig. 9 is a diagrammatic view of our invention, especially illustrating the electrical connections.

Like parts are identified by the same reference-figures throughout the several views.

Referring to the key mechanism, 1 is a switch-key adapted to be used for closing the circuits of the batteries or other electrical generators, either of the call-circuits or of the message-conveying circuits, or both. This key preferably consists in a flat bar of metal suitable for conveying an electric current and is provided with a longitudinal slot 2 and a

rib or flange 3. One edge of the key is provided with a series of notches 4 of different dimensions. The key is hung in a suitable frame 5 by means of a pin 6, which engages in the slot 2, and a bracket 7 is provided with spring-actuated studs 8, which impinge on opposite sides of the key, Fig. 6, and normally in the rear of the rib 3, the arrangement being such that the key is held by the bracket in an angular position free to move longitudinally into and out of contact with an electrode 10, supported by but insulated from the frame and preferably formed of spring metal. The other pole of the circuit or circuits to which the electrode 10 belongs is connected with the frame 5, as at 11 in Fig. 1, and it is therefore obvious that the key is adapted to close such circuits when brought into contact with the electrode 10.

The key is actuated by means of a series of pins 15, movably mounted in a carrier 16, which preferably consists in a rotary disk supported in suitable bearings in the frame 5. In the construction shown the pins are inserted transversely through an annular series of holes in the disk and are adapted when pushed outwardly on the side of the disk occupied by the key to engage in the notches 4 of the latter if in registry with such notches. Normally, however, the pins are all pushed inwardly on that side of the disk occupied by the key, out of the path of the latter, this being accomplished by providing a guide 17, against which the pins impinge when the disk is rotated, and are thereby crowded inwardly in succession on that side after having been pushed out.

The disk may be rotated by any suitable means for applying power. In the drawings, Fig. 5, we have shown a weight 18 connected with a chain 19 and adapted to communicate motion to the disk 16 through a sprocket-pulley 20 and disk-supporting shaft 21, the chain being wound up at intervals to raise the weight in the customary manner for weight-actuated mechanisms. It is obvious, however, that any other means for actuating the carrier may be substituted for the weight, as desired.

The disk 16 is provided with three ratchet-rings 23, 24, and 25 on its periphery. The

ring 24 is secured to or formed integrally with the disk, while the rings 23 and 25 are capable of an independent annular movement, limited by stops 26, which engage in recesses 28 and 29 in the respective rings. It will be observed that the recesses 28 in the ring 23 correspond in length with two of the teeth of the ratchet, while the recesses 29 in the ring 25 correspond in length with three teeth of the ratchet. Both of the rings 23 and 25 are connected with the disk 16 by spring-tension connections 30, adapted to draw the rings forwardly in the direction of the movement of the disk, so that the stops 26 are normally in contact with the rear ends of the recesses 28 and 29 of the respective disks.

31 is a hooked-shaped disk-holding pawl adapted to engage the teeth of the ratchet 24, and thus hold the disk 16 from rotating with the force exerted by the disk-actuating mechanism. This pawl is provided with an upwardly-projecting arm 32, connected with the frame by a spring 33 and provided with a cross-bar 34. This spring 33 holds the pawl normally in engagement with the ratchet 24.

35 and 36 are oppositely-projecting ring-holding pawls adapted to engage the teeth of the ratchets 23 and 25, respectively, to hold the ratchets from rotating. These pawls are provided with upwardly-extending arms 37, connected with the frame by springs 38, which are adapted to hold the pawls normally out of engagement with their respective ratchets. The arms 37 are disposed with reference to the cross-bar 34 so that as either of the pawls 35 or 36 moves into engagement with its respective ratchet the arm 37 of the engaging pawl will impinge against the bar 34 and lift the pawl 31 out of its engagement with the ratchet 24, when the disk 16 will be permitted to revolve until one of the stops 26 engages against the opposite end of the recess in that ratchet-ring which is engaged by one of the ring-holding pawls, when the disk will also be held by the ring until the ring-holding pawl is released. As soon as this pawl is released, however, the pawl 31 again engages the disk-ratchet 24 and the ring is drawn forwardly by its spring connection 30 to its normal position with reference to the disk. It will therefore be understood that if the pawl 35 be actuated into engagement with the ratchet-ring 23 the disk will be advanced a distance equal to the length of the recess 28 therein, or of two of the ratchet-teeth, while if the pawl 36 be actuated into engagement with the ratchet-ring 25 the disk will be advanced a distance equal to the length of the recess 29 therein, or three ratchet-teeth, in the construction shown in the drawings.

For actuating the pawls we have provided electromagnets 40 and 41, arranged to actuate armatures 42 and 43, secured to the arms 37 of the ring-holding pawls 35 and 36, respectively. By energizing the magnet 40 the armature 42 is actuated to move the pawl 35 into engagement with the ratchet-ring 23 and

lift the pawl 31 out of engagement with the disk-ratchet 24, thus permitting the disk to advance two notches, as heretofore explained. 70 By energizing the magnet 41 the armature 43 is actuated to move the pawl 36 into engagement with the ratchet-ring and also lift the pawl 31 and permit the advancement of the disk three notches. By energizing the 75 respective magnets alternately or successively with a varied number of impulses it is obvious that a substantially unlimited differentiation in the movement of the pin-supporting carrier or disk 16 can be secured, and by 80 providing means for operating the key-actuating pins in concurrence with the movement of the disk it is also obvious that such pins may be actuated in various combinations to fit a great variety of keys, each of 85 which may be actuated independently, the movement of each key being dependent upon its formation with notches in which the actuated pins will register.

To actuate the pins 15, we have provided 90 electromagnets 45 and 46, the armatures 47 and 48 of which are connected with pin-adjusting levers 44 and 49, respectively. The lever 44 is arranged to move independently and is adapted when moved in one direction 95 to push one of the pins 15 into a position to engage the key 1. The lever 49 is similarly formed, but is provided with an arm 50, which is also adapted to engage and actuate the lever 44, whereby as the lever 49 is actuated two of the pins 15 will be adjusted in a position to engage the key by the co-operative movement of the two levers. The pins are adjusted at a point below the key and the continued movement of the disk 16 brings 105 them into contact therewith. Whenever the pins register with the notches 4 of the key the movement of the disk will cause them to enter such notches and lift the key; but as soon as one of the pins fails to so register it will push the key backwardly until the rib 3 passes the studs 8, when the key will drop free of the pins to its lowest position, the key swinging forwardly by gravity to its original position as soon as the upper end of the rib 110 3 is in a position to pass under the studs 8.

In the construction shown each pin corresponds in position to a notch on the ratchet-rings 23 and 25, and as these rings are moved a distance equal to the length of the two notches and three notches, respectively, while the pin-actuating levers operate but one or two pins, respectively, one of the pins will be skipped with each successive stroke of the pin-actuating levers. The notches of 120 all the keys are of two kinds only, formed to receive either one or two pins, and as the key of each instrument is provided with a different set or combination of these one-pin and two-pin notches it is obvious that none 125 of the keys will reach the electrode 10 except that key in which the notches are adapted to register with the pins which are actuated.

The electromagnets 41 and 40 are included

in the circuit of the line and may be operated either with a double circuit, one for each magnet, or by the quadruplex system with a single circuit. The electromagnets 45 and 46 may be included in circuit with an independent local battery, or located on shunt-lines from the battery which actuates the main coils. In the drawings we have shown an independent local battery 55, having one pole connected in parallel through the electromagnets 45 and 46, conductors 57 and 58, brushes 59 and 60, and conductors 61 and 62 to the electrodes 63 and 64, respectively located in the stops 26 for the ratchet-rings 23 and 25. With this construction it will be observed that when either of the pawls 35 or 36 is actuated to hold its respective ring and release the ratchet 24 and disk 16 the latter will move forwardly until the ring held by the pawl engages the stop 26, when a contact is formed between the electrode in such stop and the ring and the circuit of the battery 55 closed through the pin-actuating electromagnet which is in electrical connection 25 with such electrode, the magnet being thereby energized and the pin-actuating levers set in motion through its respective armature. In the construction shown the electromagnet 45 is in electrical communication with the electrode 63, which is located in the stop 26 of the ring 23, while the electromagnet 46 is similarly in electrical communication with the electrode 64, located in the stop 26 of the ring 25. It is therefore evident that the 30 pawl-actuating electromagnet 40 and the pin-actuating electromagnet 45 will act concurrently through the medium of the ratchet-ring 23, while the magnets 41 and 46 will also act concurrently through the medium of the ring 25. The magnets 45 and 46 are thus energized successively or in alternation to actuate pins 15 in correspondence with the particular combination of long and short notches of the key pertaining to the desired station, 35 when the key will have been elevated by the pins into contact with the electrode 10 and the signaling-circuit closed, as heretofore explained, either for the purpose of sounding an alarm, sending messages, or both. As the 40 keys of all other stations have a different series of notches, it is evident that the actuated pins must fail to register at some point in the series, and when failing to so register the key will be forced backwardly and, 45 dropped.

In the drawings we have shown diagrammatically the central-office batteries 70 and 71 and a switch 72 as used for a double circuit for operating the magnets 40 and 41. We have 50 also shown a light 73 and signaling-bell 74 included in the circuit of the electrode 10; but it will be understood that various instruments may be included in such circuits and the connections made in a variety of ways to 55 suit the requirements of the system to which the invention is applied.

Reviewing the operation of our invention

and assuming that the light 73 and signaling-bell 74 are to be controlled thereby, it will be observed that the particular station shown in 70 the drawings is provided with a series of notches which, read from the top of the key downwardly, consists in a combination of two long, one short, two long, and two short notches. To operate this key, therefore, the 75 operator at the central station will move the switch-lever to form two successive contacts with the electrode 76, then one contact with the electrode 75, then two at 76, followed by two more at 75. For all contacts at 76 the 80 circuit of the battery 71 will be closed and the magnet 41 energized, with a resulting three-notch movement of the carrier or disk 16, which closes the circuit of the local battery 55 through the medium of the ring 25 85 contacting with the electrode 64, and thus energizes the electromagnet 46 and the levers 49 and 44, whereby two of the pins 15 are pushed into the path of the key. The teeth between the notches in the key correspond in 90 width to the space occupied by one pin on the disk, which pin is skipped by the levers, owing to the fact that the movement of the disk is equal to the space occupied by three pins or ratchet-notches, while the levers actuate but two of the pins. The two pins first 95 actuated are adapted to register with the first notch on the key, and the continued movement of the disk carries the pins into such registry and lifts the key accordingly. The 100 next two pins which are actuated will register with the next notch on the key and continue to elevate the latter. For all contacts at 75 the circuit of the battery 70 will be closed and the magnet 40 energized, when the disk will 105 move forwardly two notches. The ring 23 will contact with electrode 63, closing the circuit of local battery 55 through the magnet 23 and actuating lever 44 to adjust a single pin 15 in a position to register with the third 110 notch on the key, which is short and adapted to receive but a single pin. When the entire combination has been sprung, the key will have been lifted into contact with the electrode 10, closing the local signaling-circuit, 115 which includes the light and signal-bell, as illustrated. Assuming, however, that a single pin should be adjusted where two are required, it is obvious that the key would not be lifted the necessary distance to provide 120 for the registry of the pin next adjusted. On the other hand, if two pins are adjusted where the key-notch will receive but one, one of the pins will impinge on an intervening tooth. In either case the key will be pushed backwardly by the non-registering pin and will fall to its original position, as heretofore explained. As the electrode 10 is elastic, the key in contact therewith may be easily discharged to its original position by adjusting either 125 double or single pins.

All the keys should be uniformly provided with an initial notch of the same character—i. e., it should be either single or double—so

that by continuously adjusting the pins to register with notches of the opposite character all keys on the circuit may be adjusted to the initial position.

5 It will be understood that where our invention is applied to an annunciator system such as is used in hotels, &c., all the instruments may be connected in series on a single line with shunts for operating the key-actuating devices and signaling-bells. In telephone-service a number of instruments may be connected in series on a multiple party-line, rendering the same as private for each individual as a single party-line would be. For telegraphic and alarm circuits, also, each station may be individualized at pleasure and independent communication had therewith. For lighting-circuits our invention may also be employed where it is desired to turn on the lights separately. In other words, our invention is adapted to be used in connection with any kind of an electrical circuit having a plurality of stations.

Having thus described our invention, what 25 we claim as new, and desire to secure by Letters Patent, is—

1. In a circuit-closing mechanism for electrical stations, the combination of a circuit-closer at each station having individual characteristics; a carrier located at each station and provided with a series of elements adapted to be adjusted in accordance with the individual characteristics of the circuit-closer at such station; an electromagnetic device 30 controlling the movement of the carrier; and means for definitely limiting the length of the carrier movement for any one electrical impulse.

2. In a circuit-closing mechanism for electrical stations, a carrier at each station provided with differentiating elements; a plurality of devices for mechanically limiting the movement of the carrier; and electromagnetic means for independently operating said devices, whereby the movement of the carrier 45 may be divided into fixed differential distances of either equal, or unequal length.

3. In a circuit-closing mechanism for electrical stations, a carrier at each station provided with differentiating elements; and electrically-controlled mechanism for holding said carrier and permitting its movement at fixed distances of equal, or unequal length, according to the will of the operator.

55 4. In a circuit-closing mechanism for electrical stations, a carrier at each station provided with differentiating elements; means for driving the carrier; stopping devices adapted to move with the carrier, but capable, respectively, of differently-limited independent movement; and electrically-controlled mechanism for alternately engaging the carrier, and any one or more of the stopping devices, at the selection of the operator.

65 5. In a circuit-closing mechanism for electrical stations, a carrier at each station provided with differentiating elements; means

for driving the carrier; stopping devices adapted to move with the carrier, but capable, respectively, of differently-limited independent movement; means for restoring the stopping devices to their original position after such independent movement; and electrically-controlled mechanism for alternately engaging the carrier and any one or more of the stopping devices, at the selection of the operator.

6. In a circuit-closing mechanism for electrical stations, a carrier at each station provided with differentiating elements; electrically-controlled mechanism for holding said carrier and permitting its movement at fixed distances of equal, or unequal length, according to the will of the operator; and similarly-controlled mechanism arranged to operate concurrently with the holding mechanism for adjusting the differentiating elements in position for contact with the circuit-closer.

7. In an electrical circuit connected with a plurality of stations, the combination of circuit-closing keys for the stations, having characteristics different from the keys of other stations; carriers provided with a series of key-actuating elements; electromagnets controlling the movement of said carriers; and electromagnetic means for adjusting said elements in any carrier to fit the individual characteristics of its respective key.

8. In an electrical circuit connected with a plurality of stations, the combination of a circuit-closing key for each station, having characteristics different from the keys of other stations; a carrier provided with a multiple series of key-actuating elements; electromagnets controlling the movement of said carrier; and electromagnetic means for adjusting said elements to fit the individual characteristics of any one of said keys; together with means for actuating the carrier and the key-actuating elements.

9. In an electrical circuit connected with a plurality of stations, the combination of keys for the stations, each having characteristics different from the keys of other stations; key-actuating devices at the stations, adapted to be adjusted to the individual characteristics of one of the keys; means for actuating said devices; and electromagnetic means for adjusting the key-actuating devices, said devices being ineffective to move a key into operative position except when adjusted to the individual characteristics of such key.

10. In an electrical circuit connected with a plurality of stations, the combination of keys for the stations having characteristics different from the keys of other stations; key-actuating devices at the stations, adapted to be adjusted to the individual characteristics of the keys; means for actuating said devices; electromagnets controlling the movement of the key-actuating devices; electromagnets for adjusting the key-actuating devices to the individual characteristics of its respective key; and means for energizing certain of said

controlling and adjusting electromagnets concurrently; said key-actuating devices being ineffective to move a key into operative position, except when adjusted to the individual characteristics of such key.

11. In an electrical circuit connected with a plurality of stations, the combination of circuit-closing keys for the stations having characteristics different from the keys of the other stations; key-actuating devices at the stations, adapted to be adjusted to the individual characteristics of the keys at such stations; means for actuating said devices; electromagnets for adjusting the key-actuating devices to the individual characteristics of the keys at such stations; means for energizing certain of the adjusting and controlling magnets concurrently; and means for readjusting the key-actuating devices to an inoperative position, except when adjusted to the individual characteristics of such key.

12. In an electrical circuit connected with a plurality of stations, the combination of circuit-closing keys for the stations, each having characteristics different from the keys of other stations; key-actuating devices adapted to be adjusted to the individual characteristics of the keys; means for actuating said devices; electromagnets controlling the movements of said devices; electromagnets for adjusting said devices to the individual characteristics of the keys; said devices being ineffective to move a key into operative position, unless adjusted to the individual characteristics thereof; together with means for communicating motion from said devices to restore the keys to their initial position.

13. In an electrical circuit connected with a plurality of stations, the combination of circuit-closing keys for the stations, each having characteristics different from the keys of the other stations; a carrier at each station, provided with a series of key-actuating elements; means for actuating the carrier; electromagnetic means for controlling the movement thereof; electromagnetic means for adjusting the key-actuating elements of the carrier to register with the individual characteristics of their respective keys; and key-supporting devices adapted to release the respective keys and permit them to return to their initial position, when the adjusting actuating elements of the carrier fail to register with the individual characteristics of such keys.

14. In an electrical circuit connected with a plurality of stations, the combination of circuit-closing keys for the stations, each having characteristics different from the keys of the other stations; a carrier at each station, provided with a series of key-actuating elements; means for actuating said carrier; electromagnetic means for adjusting the key-actuating elements of the carriers to register with the individual characteristics of their respective keys.

15. In an electrical circuit connected with a plurality of stations; the combination of cir-

cuit-closing keys for the stations, each having characteristics different from the keys of the other stations; a carrier at each station, provided with a series of key-actuating elements; means for actuating said carrier; and electromagnetic means for controlling the movement of the carrier.

16. In an electrical circuit connected with a plurality of stations; the combination of circuit-closing keys for the stations, each having characteristics different from the keys of the other stations; a carrier at each station, provided with a series of key-actuating elements; means for actuating said carrier; electromagnetic means for controlling the movement of the carrier; and means for restoring the keys to their initial positions.

17. In an electrical circuit connected with a plurality of stations; the combination of circuit-closing keys for the stations, each having characteristics different from the keys of the other stations; a carrier at each station, provided with a series of key-actuating elements; means for actuating said carrier; electromagnetic means for adjusting the key-actuating elements of the carriers to register with the individual characteristics of their respective keys; and means for automatically restoring the key-actuating elements to an inoperative position, after said elements have actuated the key.

18. In an electrical circuit connected with a plurality of stations; the combination of circuit-closing keys for the stations, each having characteristics different from the keys of the other stations; a carrier at each station, provided with a series of key-actuating elements; means for actuating said carrier; electromagnetic means for adjusting the key-actuating elements of the carriers to register with the individual characteristics of their respective keys; and means for restoring the keys to their initial positions.

19. In an electrical circuit connected with a plurality of stations; the combination of circuit-closing keys for the stations, each having characteristics different from the keys of the other stations; a carrier at each station, provided with a series of key-actuating elements; means for actuating the carrier; a plurality of sliding connections mounted on said carrier; stops for limiting the movement of said connections, arranged to allow each such connection a different movement from the other; holding devices for said carrier; and sliding connections, and electromagnetic means for releasing said holding devices interchangeably, whereby the movement of the carrier is controlled.

20. In an electrical circuit connected with a plurality of stations; the combination of circuit-closing keys for the stations, each having characteristics different from the keys of the other stations; a carrier at each station, provided with a series of key-actuating elements; means for actuating the carrier; a plurality of sliding connections mounted on said car-

- rier; stops for limiting the movement of said connections, arranged to allow each such connection a different movement from the other; holding devices for said carrier; and sliding connections, and, electromagnetic means for releasing said holding devices interchangeably, whereby the movement of the carrier is controlled; electromagnets arranged to be switched into and out of circuit with a source of electrical current by said sliding connections; and levers adapted to be actuated by such magnets to adjust the key-actuating elements with reference to the individual characteristics of the keys.
21. In an electrical circuit connected with a plurality of stations; the combination of circuit-closing keys for the stations, each having characteristics different from the keys of the other stations; a rotary disk-carrier at each station; means for driving said carrier; a series of key-actuating elements adjustably connected with said carrier; electromagnetic means for controlling the movement of said carrier; electromagnetic means for adjusting said key-actuating devices into registry with a key; and means for securing a concurrent action of the carrier-controlling and the adjusting magnets.

22. In a circuit-closing mechanism for electrical stations, a carrier at each station; differentiating elements adapted to be supported thereby; and means, controlled by electrical impulses of variable character for regulating the carrier movement in correspondence with the character of the impulse transmitted, whereby the movement of the carrier is controlled independently of the duration of the transmitted impulses. 30

23. In a circuit-closing mechanism for electrical stations, a series of differentiating elements mounted in a suitable support at each station; and means, controlled by electrical impulses of variable character, for adjusting the differentiating elements of any one series to the desired operative, or inoperative, position, whereby such adjustment may be effected, independently of the duration of the transmitted impulses. 40

In testimony whereof we affix our signatures in the presence of two witnesses.
